UNITED STATES PATENT OFFICE

1,952,770

SHOE MACHINE

Alfred R. Morrill, Beverly, Mass., assignor to
 United Shoe Machinery Corporation, Paterson,
 N. J., a corporation of New Jersey

Application June 8, 1926, Serial No. 114,441

24 Claims. (Cl. 112—46)

The present invention relates to shoe machines and is herein shown as embodied in a machine for operating on shoes of the type in which the shoe is supported upon a jack and in which the jack and the means for operating on the shoe are moved relatively to transfer the point of operation about the shoe, and to change the relative positions of the shoe and the operating means to cause the shoe to be presented properly to the operating means as the point of operation is transferred about the shoe, all of the relative movements of the shoe and the operating means being produced and controlled by automatically acting mechanisms. While the several features of the present invention are particularly applicable to automatic shoe machines of the type above referred to, certain features of the invention are also capable of use in other types of automatic machines or in machines in which the shoe is held in position by the operator. It is also to be understood that except as defined in the claims, the several features of the invention are not limited to any particular construction or arrangement of parts.

The machine hereinafter specifically described as embodying the several features of the present invention is an automatic machine for sewing the welt and upper to the insole of a welded shoe and in many respects is similar in the construction and arrangement of its various parts to the automatic welt sewing machine disclosed in the application of the present applicant and Laurence E. Topham, Serial No. 312,366, filed July 21, 1919, on which Patent No. 1,616,714 issued February 8, 1927. The several features of the present invention will be readily understood by those skilled in the art from the following description, but it may be stated at this point that they relate generally to certain improved constructions and arrangements of parts for rendering more certain and reliable the operation of the mechanisms which automatically produce or control the changes in the relative positions of the shoe and the operating means and to certain improved constructions and arrangements of the parts of the welt sewing mechanism and of the mechanisms which act upon the shoe after the sewing of the welt has been completed.

Referring to the drawings, Fig. 1 is a view in front elevation of an automatic welt shoe sewing machine embodying the several features of the present invention; Fig. 2 is a view in side elevation of the machine with a portion of the frame broken away and looking towards the left of Fig. 1; Fig. 3 is a view in side elevation of the

machine, partly in section, looking towards the right of Fig. 1; Fig. 4 is a view in side elevation, partly in section, of the lower part of the machine showing particularly the supporting devices for the jack and the pattern cam shaft with its several series of controlling cams; Fig. 5 is a plan view of the machine; Fig. 6 is a view in front elevation, partly in section, of the upper portion of the machine; Fig. 7 is a plan view, partly in section, of the portion of the machine illustrated in Fig. 6. Fig. 8 is a detail plan view supplementing the illustration of Fig. 7; Fig. 9 is a plan view of the base portion of the machine with the jack spindle shown in section and a portion of the top plate of the machine base broken away to show underlying parts; Fig. 10 is a plan view of the base portion of the machine with the top plate of the base partly broken away and with a portion of the mechanism shown in section below the plane of Fig. 9, this figure also showing the position of the parts with the jack at the limit of its movement to the left and with the welt cutter in the act of severing the welt; Fig. 11 is a detail plan view of a portion of the mechanism for actuating the jack to pull the welt through the welt guide after the completion of the welt sewing operation; Fig. 12 is a plan view of the base of the machine similar to Fig. 11, but showing certain of the parts in section on a lower plane than Fig. 10, this figure also showing the jack as having been moved to the right and slightly towards the front after the welt severing operation; Fig. 13 is a detail sectional plan view showing certain of the parts of the driving and stopping mechanism in the positions they assume during the stopping of the machine in case of the breaking of the thread; Fig. 14 is a rear view, partly broken away, of a portion of the machine; Figs. 15 and 16 are detail perspective views of devices associated with the pattern cam shaft and which are actuated at the completion of the sewing operation; Fig. 17 is a detail sectional view of a portion of the driving mechanism taken on the line 17—17 of Fig. 13; Fig. 18 is a detail sectional view of a portion of the mechanism illustrated in Fig. 17, but looking in the opposite direction, and taken on the line 18—18 of Fig. 13; Fig. 19 is a detail sectional view similar to Fig. 18, but taken on a different plane; Fig. 20 is a detail sectional view taken on the line 20—20 of Fig. 18; Fig. 21 is a detail plan view, partly in section, of a portion of the mechanism through which the pattern cam shaft is driven, and showing also a portion of the auxiliary mechanism for driving the

105

110

cam shaft after the main drive is thrown out and also a portion of the mechanism for reversely driving the pattern cam shaft when the machine is stopped upon the breakage of thread; Fig. 22 is a detail plan view of certain of the parts illustrated in Fig. 21; Fig. 23 is a detail plan view of certain of the parts illustrated in Fig. 21, but showing the position which they assume during the stopping of the machine at the end of the 10 sewing operation; Fig. 24 is a detail sectional plan view similar to Fig. 21, but taken on a lower plane and showing particularly the mechanism for disconnecting certain of the gears in the main driving train when the pattern cam shaft is rotated 15 by the auxiliary mechanism; Fig. 25 is a sectional elevation, taken on the line 25—25 of Fig. 24; Fig. 26 is a detail sectional view taken on the line 26—26 of Fig. 24; Fig. 27 is a detail plan view of certain mechanisms at the upper end of 20 the pattern cam shaft illustrating particularly the means actuated by the cam shaft for opening the main driving clutch in case the stopping mechanism fails to operate at the completion of the operations performed by the machine; Fig. 28 25 is a detail sectional view illustrating the means for preventing the closing of the main driving clutch while the levers actuated by the pattern cam shaft are out of engagement with their cams; Fig. 29 is a detail view in side elevation of the 30 lever which opens the main driving clutch; Fig. 30 is a detail sectional view of the upper end of the rock shaft upon which the pattern cam levers are mounted; Fig. 31 is a detail sectional plan view illustrating particularly the construction of 35 one of the levers actuated by the cam shaft; Fig. 32 is a detail view showing in side elevation the mechanism illustrated in Fig. 31 and also the operating handles at the upper end of the pattern cam shaft and the rock shaft upon which the cam 40 levers are mounted; Fig. 33 is a detail sectional plan view illustrating particularly a checking or snubbing device applied to one of the cam levers; Fig. 34 is a horizontal sectional view of the cylinder and piston of the snubbing device; Fig. 35 is 45 a sectional view taken on the line 35—35 of Fig. 33; Fig. 36 is a detail cross sectional view taken on the line 36—36 of Fig. 35; Fig. 37 is a detail sectional plan view illustrating particularly a snubbing device applied to another one of the 50 cam levers associated with the pattern cam shaft, the plane of the figure being indicated by the line 37—37 on Fig. 39; Fig. 38 is a detail sectional view taken on the line 38—38 of Fig. 37; Fig. 39 is a detail sectional view taken on a plane passing 55 centrally through the cylinder of the snubbing device substantially at right angles to the plane of Fig. 38; Fig. 40 is a detail view showing a side elevation of the devices for depressing the jack and moving it to the front of the machine at 60 the conclusion of the welt sewing operation; Fig. 41 is a view similar to Fig. 40, but showing the parts, partly in section, and in a different position; Fig. 42 is a view in front elevation of the parts illustrated in Figs. 40 and 41; Fig. 43 is 65 a view in side elevation, partly broken away of the sewing machine head looking towards the left, as viewed in Fig. 1; Fig. 44 is a sectional elevation of the sewing machine head looking in the same direction as Fig. 43 taken on a plane substantially 70 coincident with that of the axis of the channel guide; Fig. 45 is a detail sectional elevation of a portion of the sewing mechanism looking towards the right, as viewed in Fig. 1; Fig. 46 is a view similar to Fig. 45 taken on a plane substantially 75 coincident with that of the channel guide axis;

Fig. 47 is a detail sectional view showing on a larger scale the portion of the mechanism illustrated in Fig. 44; Figs. 48 and 49 are detail elevational sectional views illustrating particularly the action of the switch cam on the lever through which the thread arm and thread cutter and holder are actuated; Fig. 50 is a plan view, partly in section, of the mechanism illustrated in Fig. 47; Fig. 51 is a sectional plan view similar to Fig. 50, but taken on a somewhat lower plane; Fig. 52 is a sectional plan view taken on a somewhat lower plane than Fig. 51; Fig. 53 is a detail vertical sectional view looking towards the rear of the machine and illustrating particularly the mechanism for supporting and actuating the welt guide; Fig. 54 is a detail sectional plan view taken on the line 54—54 of Fig. 53; Fig. 55 is a detail sectional view looking from the rear and taken on the line 55—55 of Fig. 54; Fig. 56 is a detail sectional view illustrating the action of the welt slashing mechanism; Fig. 57 is a detail perspective view of the welt slashing knife; Fig. 58 is a detail sectional plan view taken on the line 58—58 of Fig. 56; Fig. 59 is a detail view of the cams and cam lever for actuating the 100 thread arm, thread cutter and holder; Fig. 60 is a detail sectional view taken on the line 60 of Fig. 59; Fig. 61 is a detail sectional view taken on the line 61 of Fig. 59; Fig. 62 is a detail view illustrating the welt cutter; Fig. 63 is a view similar to Fig. 62 with the parts in a different position; Fig. 64 is a detail sectional plan view of the parts illustrated in Fig. 62; Fig. 65 is a detail view showing in front elevation the parts illustrated in Figs. 62 to 64; Fig. 66 is a detail view illustrating the mechanism through which the machine is stopped in case the thread breaks; Fig. 67 is a view showing a portion of the mechanism illustrated in Fig. 66 in a different position; and Fig. 68 is a detail sectional view on the line 115 68—68 of Fig. 67.

The general organization of the machine illustrated in the drawings is the same as that of the machine disclosed in the patent above referred to. The machine comprises sewing mechanism mounted in a sewing head or frame 69 supported upon the base 70 of the machine (see Figs. 1, 2, 3, 4 and 9), a shoe supporting jack comprising a toe supporting arm 71 rigid with a hollow spindle 72 and a heel supporting arm 73 pivoted at its lower end upon the upper end of the spindle 72, a jack supporting structure comprising a horizontal arm 74 in the forward end of which the lower end of the jack spindle is rotatably mounted by means of a gimbal joint, a support 75 upon which the arm 74 is mounted to swing vertically, a frame 76 pivotally mounted at its lower end in the machine base so as to be capable of swinging about a horizontal axis and upon which the support 75 is mounted so as to swing about a substantially vertical axis, a vertical cam shaft 77 mounted in the machine base and carrying a series of cams 78 and a driving and stopping mechanism supported in a frame 79 mounted on the machine base at one side of the frame 69 of the sewing mechanism. The pattern cam shaft 77 makes one complete rotation during a complete cycle of operations of the machine, this cycle consisting of the sewing of the inseam, the severing of the thread and welt at the completion of the sewing, the moving of the jack to the front of the machine away from the sewing devices, and the rotating of the jack in a reverse direction to bring it to its initial position.

During the sewing operation, tipping and ro-

80

140

145

150

tating movements are imparted to the shoe to maintain the shoe at all times in the proper position with relation to the sewing instrumentalities, tipping movements being imparted by moving the lower end of the jack spindle forwardly and rearwardly of the machine and laterally, and rotating movements being imparted by rotating the jack spindle. For moving the lower end of the jack spindle forwardly and rearwardly, a cam lever 80 is provided, one arm of which is pivotally connected to the frame 76 and the other arm of which is arranged to engage one of the cams 78 on the pattern cam shaft. The lateral movements of the lower end of the jack spindle are produced by oscillating the support 75, the lower end of which is provided with a forwardly projecting arm 81 which is connected by means of a link 82 to one arm of a lever 83, the other arm of which is engaged by a cam on the pattern cam shaft. To rotate the jack spindle, a wheel is provided at the lower end of the spindle around which a cord 84 passes. One end of the cord after passing over a pulley near the inner end of the arm 74 is secured to a wheel 85 and the other end of the cord 25 after passing over a pulley near the inner end of the arm 74 and over a pulley 86 on the base of the machine leads to a weight 87. The hub of the wheel 85 is provided with a pinion 850 which meshes with a segmental rack on the outer 30 end of a lever 88, the other end of which lever is engaged by a cam on the pattern cam shaft (see Fig. 37).

During the sewing operation the shoe is fed by the feeding devices of the sewing mechanism and also by a feed lever which is actuated from the cam on the pattern cam shaft and which controls the longitudinal position of the shoe in the machine. The feed lever (see Figs. 3 and 9) comprising an arm 89 pivotally mounted so as to swing in a horizontal plane, is connected at its forward end by means of a bar 90 to the toe supporting arm of the jack. The feed lever is connected by means of links 91 and 92 to one arm of a lever 93, the other arm of which engages a cam on the pattern cam shaft. The links 91 and 92 are pivotally connected together and to the free end of a swinging guiding link 94. The link 94 is fulcrumed upon a lever 95 which is held locked in position during the operation on a shoe. To adapt the machine for operation on shoes of different sizes, the lever 95 is pivotally mounted upon the machine base so that it can be adjusted to change the position of the fulcrum of the swinging guiding link 94. The fulcrum carrying lever 95 is held locked in adjusted position during the operation on the shoe by mechanism comprising a rod 96 pivotally connected to the rear end of the fulcrum carrying lever 95 and arranged to slide in a block pivotally mounted on the machine base. The rod 96 is engaged by the inner cam shaped ends of short levers 97 mounted in the block and the outer ends of these levers are connected by a pin and slot construction with a cross bar 98. This cross bar is pivotally mounted on the rear end of a rod 99, the forward end of which is pivotally connected to a bar 100. The bar 100 at one end is connected to an arm 102 and near its other end is connected by a link 103 to one arm of a lever 104, the hub of which is arranged to be engaged by a latch 105. During the operation on a shoe, the lever 104 is held by the latch 105 and the fulcrum carrying lever 95 is locked in position. The placing of a new shoe on the jack acts to release the lever 104, as will herein-after appear and as fully explained in the patent

above referred to, so that the fulcrum carrying lever 95 is unlocked, and adjustment of the mechanism for actuating the feed lever can be made by the movement of the jacked shoe to starting position in the machine. The fulcrum carrying lever 95 is locked in position on starting the machine by means of a pin 106 on a horizontally arranged bar 107, which pin as the bar is moved to the right, swings the lever 104 until it is engaged by the latch 105. The bar 107 is a part of the starting mechanism and is connected by means of a bell crank lever and connecting rod to the starting treadle of the machine.

At this point, it may be noted that the bar 100 of the mechanism for locking and unlocking the fulcrum carrying lever of the feed mechanism is also utilized to adjust the speed of the pattern cam shaft in accordance with the size of the shoe to be operated on, the arm 102, to which one end of the bar 100 is connected, acting when moved in either direction, to shift the adjustable cam plate 108 of the variable speed mechanism through which the pattern cam shaft is driven. This cam plate is pivotally mounted at one end on the machine frame and at the other end has a gear toothed connection with an arm 109 fast on the rock shaft carrying the arm 102. The arm 102 is moved into the proper position by a longitudinal movement of the controller bar 100 imparted thereto by the engagement of a pin 110 on a forward extension of the lever 95 with one of two inclined surfaces formed on the end of the bar 100 remote from the arm 102, this engagement taking place during the forward movement of the bar 100 as the machine is started into operation by the depression of the starting treadle.

The construction so far described is substantially the same as that of the machine disclosed in the patent hereinbefore referred to. From an inspection of Figs. 1, 3, 9 and 12, it will be obvious that the action of the cord 84 and weight 87 is to rotate the jack in a reverse direction and to exert a force on the jack supporting structure tending to maintain the cam levers through which the tipping movements are imparted to the jack in contact with their cams. A feature of the present invention is embodied in a structure whereby the cord 84 and weight 87 are also utilized to exert a force on the feeding arm 89 of the jack feeding mechanism and the fulcrum carrying lever 95, tending to keep the cam lever 93 through which the feeding lever is actuated in contact with its cam, and tending to move the fulcrum carrying lever 95 towards one limit of its adjustment. In the construction illustrated, the cord 84 instead of being attached directly to the weight 87 passes around a pulley 111 secured to the weight (see Figs. 1, 3 and 9) and then passes upwardly over a pulley 112 on the machine frame, and then horizontally around a pulley 113, also mounted on the machine frame, then around a pulley 114 mounted on the fulcrum carrying lever 95, then around a pulley 115 mounted on the pivot of the fulcrum carrying lever, and is finally secured to the feed lever.

Another feature of the present invention is embodied in a device or devices for checking or retarding the reverse rotation of the jack and the movements of the levers actuated by the pattern cam shaft under the influence of the weight 87 when the cam levers pass off of the high portions of their cams at the completion of the rotation of the pattern cam shaft. In the construction illustrated in the drawings, a checking

150

or snubbing device is associated with the cam lever 93 from which the feed lever is actuated and with the cam lever 88 through which the wheel 85 is rotated to impart rotating movements 5 to the jack.

The snubbing device associated with the lever 93 (see Figs. 33 to 36 inclusive) comprises a cylinder 116 in which a piston 117 is mounted to reciprocate, the cylinder being pivotally supported at one end on the machine frame and the piston being connected to the lever 93 by means of a connecting rod 118. The cylinder 116 is closed at both ends and is filled with a suitable fluid such as oil. A passageway 119 extends longitudinally through the piston and in order to permit a free flow of the fluid in one direction and to obstruct the flow of fluid in the opposite direction a ball valve 120 is provided in the passageway 119. The piston is thus substantially 10 free to move in one direction, but its movement is retarded in the opposite direction. To regulate this retarded movement, a relief passageway 121 extends longitudinally through the piston 117 and the flow of oil through this passageway is 15 regulated by means of an adjustable pin 122 arranged transversely of the passageway.

The snubbing device for retarding the movements of the wheel 85 and cam lever 88 comprises an oscillating segmental piston 123 mounted to move back and forth in a semi-cylindrical chamber formed in a casing 124 (see Figs. 37, 38 and 39). For convenience of construction, the casing 124 is formed with a cylindrical chamber one-half of which is filled by a stationary semi-cylindrical block 125. The piston 123 projects from a vertical shaft 126, the lower end of which is reduced in size and is journaled in the casing and the upper end of which is journaled in a plug 127 which closes the upper end of the chamber in the casing. To the lower end of the shaft 126 is secured an arm 128 formed at its outer end as a segmental gear which meshes with the pinion 850 on the hub of the wheel 85. The wheel 85 is thus connected to the piston 123 so that 20 the piston is oscillated in the chamber by the forward and backward movement of the wheel. The chamber in the casing 124 is filled with suitable fluid such as oil, and in order to retard the movement of the piston in one direction while 25 permitting it to move with substantial freedom in the opposite direction, the piston is provided with a passageway 129 leading from one side of the piston to the other and with a check ball valve 130 to prevent the flow of liquid in one direction. To provide for a comparatively slow movement of the liquid from one side of the piston to the other, a passageway 131 is formed in the block 125 communicating with the chamber in the casing 124 at opposite sides of the 30 piston. Relief passages 132 and 133 are also provided in the bottom of the casing 124 so that the liquid is allowed to flow freely from one side of the piston to the other when the piston is in certain positions, as for instance, when it is in 35 the positions it assumes at the time the shoe is being operated upon on either side at the junction of the shank and forepart. At these points in the operation on the shoe, a reverse rotation is imparted to the shoe and by reason of these 40 relief passages 132 and 133, these reverse movements are not resisted by the snubbing device. To provide a piston operating mechanism having the requisite amount of strength, the arm 128 which is connected to the piston shaft is made 45 integral with and forms a part of a yoke 134

which straddles the casing 124 and which is provided with a slot engaging a key 135 formed at the upper end of the piston shaft 126.

The illustrated machine, like the machine of the patent hereinbefore referred to, is provided with a driving mechanism from which the sewing mechanism and the pattern cam mechanism are driven, with a stopping mechanism which at the completion of the sewing operation is automatically thrown into operation and which acts to disconnect the sewing and pattern cam mechanism from the driving mechanism, with an auxiliary mechanism normally idle, but which is automatically connected to the driving mechanism when the sewing and the pattern cam mechanisms are disconnected, and with means actuated by the auxiliary mechanism for causing the welt to be severed and the jack to be moved outwardly and reversely rotated to its initial position.

The sewing mechanism and the pattern cam mechanism are driven from a sleeve 136 (see Figs. 1, 2, 6, 14 and 28) mounted loosely on a vertical shaft 137 which is driven continuously from an electric motor through reducing gearing, the last pinion 138 of said gearing meshing with a gear 100 formed on the periphery of a friction clutch member 139 secured to the shaft. The sleeve 136 is provided at its upper end with a friction clutch member 140 cooperating with the clutch member 139. A spiral gear 141 is formed on the sleeve 136 105 and this gear meshes with a spiral gear 142 secured to the cam shaft of the sewing mechanism. The spiral gear 141 also meshes with a spiral gear 143 secured to the upper end of a vertical shaft 144. This shaft at its lower end is provided with a clutch block 145 connected to the shaft by a key 110 on the block engaging a transverse slot in the lower enlarged end of the shaft. The lower face of the block 145 is provided with teeth to engage correspondingly shaped teeth on the upper surface of the enlarged upper end 146 of a short vertical shaft 147. Surrounding the shaft 147 is a sleeve 148 which is driven from the shaft 147 115 through a variable speed mechanism and which is provided at its lower end with a pinion 149. From the pinion 149, the pattern cam shaft is 120 driven through a train of gears comprising a gear 150 meshing with the pinion 149, a gear 151 concentric with the gear 150 and secured thereto, a gear 152 meshing with the gear 151 and secured to 125 the lower end of a short vertical shaft 153, an elongated pinion 154 fast on the shaft 153, a gear 155 meshing with the pinion 154, and a series of gears 156 secured together and to the gear 155 arranged 130 to mesh with a gear 157 at the upper end of the pattern cam shaft. The pattern cam shaft is thus driven continuously so long as the members of the main driving clutch 139-140 are engaged, the speed of rotation depending on the adjustment of the variable speed mechanism between 135 the shaft 147 and the sleeve 148. This variable speed mechanism (see Figs. 17 and 21) comprises a ratchet wheel 158 fast on the shaft 147, a series of pawl carriers 159 pivotally mounted on the upper end of the sleeve 148, a pawl 160 mounted on 140 each pawl carrier and spring pressed into engagement with the ratchet 158 and the adjustable cam plate 108 hereinbefore referred to provided with a cam groove engaging pins 161 projecting upwardly from the pawl carriers.

The pattern cam shaft is provided with a series of sets of cams as in the machine of Patent No. 1,616,714 above referred to. These cams are brought into cooperative relation with the cam levers by a longitudinal adjustment of the cam 145 150

shaft, the construction for producing this adjustment comprising a shaft 162 (see Fig. 4) passing axially through the pattern cam shaft 77. The lower end of the shaft 162 has a screw threaded engagement with a vertical adjustable sleeve 163 mounted in the lower portion of the machine base. The pattern cam shaft 77 rests upon the upper end of the sleeve 163 so that a vertical adjustment of the sleeve produces a corresponding adjustment of the cam shaft. At its upper end above the top plate of the machine base the shaft 162 is provided with an arm 164 (see Fig. 5) by which the shaft may be turned manually to adjust the cam shaft. To hold the cam levers away from the cams while the cam shaft is being adjusted, the shaft 165 upon which the cam levers, with the exception of the lever 93, are mounted, is provided with shouldered collars 166 (see Figs. 28 and 32) which when the shaft 165 is turned by an arm 167 secured to the upper end of the shaft engage the hubs of the levers and move the cam ends of the levers away from the cams. To move the cam lever 93 through which the feed lever is actuated away from its cam, a link 168 is connected to one arm of the lever 93 (see Figs. 9, 27 and 28) and this link has a pin and slot connection with the outer end of an arm 169 secured to the shaft 165.

The stopping mechanism which at the completion of the sewing operation acts to disconnect the sewing mechanism and the pattern cam mechanism from the driving mechanism comprises a bell crank lever 170 (see Figs. 1, 2, 6 and 28), the horizontal arm of which engages a cam groove 171 in the sleeve 136 and the vertical arm of which is provided at its lower end with a hole adapted to receive a locking bolt 172 (see also Figs. 1, 7 and 8). During the sewing operation the sleeve 136 is held in its upward position with the clutch members 140-139 in engagement by means of a spring 173 (see Fig. 28) interposed between the lower end of the sleeve and a flange on a bushing 174 surrounding the shaft 137 and resting on a shoulder on the machine frame. Also during the sewing operation, the locking bolt 172 is held in retracted position so that the bell crank 170 vibrates idly. The locking bolt 172 is mounted in one end of a horizontally movable locking bolt carrier 175 (see Figs. 6, 7 and 8), the other end of which projects beyond the machine frame and is acted upon by a spring 176 which bears against a collar on the carrier and tends to move the carrier towards the left, as viewed in Fig. 6. At the end of the sewing operation, the locking bolt 172 is released and is forced by its spring into the hole in the bell crank lever as soon as the hole in the bell crank is brought into alignment with the locking bolt. This occurs at a predetermined point in the rotation of the sleeve 136 and of the actuating cam shaft of the sewing mechanism and locks the lower end of the vertical arm of the bell crank to the locking bolt carrier. Continued rotation of the sleeve 136 oscillates the bell crank in a direction to move the locking bolt carrier to the right, as viewed in Fig. 6, against the tension of the spring 176. A partial return movement is permitted to the locking bolt carrier and then its return movement to the left is stopped by a spring pressed latch lever 177 (see Fig. 1), a projection on the upper side of which engages a shoulder on the locking bolt carrier. The lower end of the vertical arm of the bell crank is now held stationary and continued rotation of the sleeve 136 moves the sleeve downwardly, thereby

disconnecting the clutch members 140-139 and bringing a brake member 178 formed on the lower end of the sleeve 136 into engagement with a fixed brake member 179. This disconnects the sewing mechanism and the pattern cam mechanism from the driving mechanism and stops the sewing mechanism with the actuating cam shaft of the sewing mechanism in a predetermined angular position, in which position the needle is retracted from the work.

The means for holding the locking bolt 172 in retracted position during the sewing operation comprises a horizontally arranged lever 180 (see Fig. 8), one arm of which is forked and engages the inner face of a disk secured to the outer end of the locking bolt, and the other arm of which is provided with a bevel gear segment meshing with a bevel gear segment on the upwardly projecting arm of a lever 181 (see also Figs. 1 and 6). This lever is arranged to swing in a vertical plane and the arm opposite the bevel gear segment is pivotally connected to the upper end of a vertical rod 182. This rod is acted upon by a spring 183 which tends to raise the rod and the rod is provided with a lateral projection 184 (see Figs. 1, 100 13, 21, 22 and 23), which during the sewing operation is engaged by a spring pressed latch 185. The latch lever 177 which limits the movement of the locking bolt carrier to the left during the operation of the stop mechanism is provided with a slot 186 (see Fig. 1), which is engaged by a pin projecting from the lever 181 so that the latch is withdrawn from engagement with the locking bolt carrier when the rod 182 is depressed.

At the conclusion of the sewing operation the latch 185 (see Figs. 21, 22 and 23) is automatically withdrawn from the projection 184 of the rod 182 so as to set the stop motion into operation. The latch 185 is mounted to slide horizontally in guideways on the machine frame and is provided on its upper surface with a V shaped notch opening towards the rod which is engaged by a pin 187 projecting downwardly from the right hand end of a lever 188. This lever is mounted to swing in a horizontal plane and its movements either 120 forwardly or rearwardly will cause the pin 187 to retract the latch 185, thereby throwing the stop mechanism into operation.

The driving and stopping mechanism so far as described, is substantially the same as that of 125 the machine disclosed in Patent No. 1,616,714 hereinbefore referred to. In the present machine, however, the mechanism for automatically throwing the stop motion into operation is actuated directly from the pattern cam shaft 130 after it has made nearly a complete revolution. To secure this result, a block 189 is secured to the upper surface of the gear 157 at the upper end of the pattern cam shaft (see Figs. 9, 10, 12, 13 and 27) which block, after the pattern cam shaft 135 has made nearly a complete revolution, engages a lever 190 pivotally mounted at 191 and connected to a rod 192. The forward end of the rod 192 is mounted to slide in a guiding block 193 pivotally mounted on the machine frame and is 140 arranged to engage the end of a dog 194 pivotally mounted at the left hand end of the lever 188. This dog is in the form of a bell crank with one arm normally in position to form in effect a continuation of the rod 192. The dog 194 is interposed between the rod 192 and the lever 188 in order to permit the lever to be moved rearwardly when the machine is stopped on account of a mis-stitch near the end of the sewing operation, as will be hereinafter described. The arrange- 150

ment of the connections above described is such that as the pattern cam shaft nears the end of a revolution the lever 190 is rocked by the engagement therewith of the block 189, the rod 192 is moved longitudinally towards the front of the machine and the lever 188 is swung forwardly as indicated in Fig. 23 to withdraw the latch 185 and throw the stop mechanism into operation.

The auxiliary mechanism which is normally idle, but which is automatically connected to the driving shaft 137 when the sewing mechanism and the pattern cam mechanism are disconnected therefrom by the action of the stop mechanism, comprises an eccentric 195 (see Figs. 6, 13, 18 and 19) mounted to turn loosely upon a hollow stud 196 formed on the machine frame below and in axial alinement with the shaft 137. Vertically below the eccentric 195 is a clutch block 197 mounted to slide longitudinally on and to rotate with a continuously rotating shaft 198. This shaft is provided with a gear 199 which is driven from a gear 200 at the lower end of the shaft 137 through gears 201 and 202 (see Figs. 6, 7, 17 and 19). The opposed faces of the clutch block 197 and the eccentric 195 are provided with teeth through which the eccentric can be driven from the clutch block whenever the block is raised into engagement with the eccentric. The block 197 is engaged by the forked arm of a lever 203 the arm of which is provided with a projection arranged to be engaged by a projection on the lower end of a rod 204. The upper end of this rod (see Figs. 6 and 7) is connected to an arm 205 on one end of a rock shaft to the other end of which is secured an arm 206 provided with a bevel gear segment meshing with a bevel gear segment on a horizontal arm 207 of a bell crank lever, the vertical arm of which is forked and engages the flanged sleeve at the left hand end of the locking bolt carrier 175. The lower end of the rod 204 (see Figs. 17 to 19 and 21 to 23) is arranged to move vertically between two pins 208 projecting upwardly from a short lever 209 pivoted concentrically with the latch actuating lever 188. The lever 209 is acted upon by two spring pressed plungers 210 mounted in the lever 188 and arranged so that their tendency is to keep the lever 209 in alinement with the lever 188. With this construction, when the lever 188 is swung forwardly to throw the stop mechanism into operation the lever 209 will be retained in its original position by reason of the engagement of the side of the projection on the rod 204 with the projection on the lever 203. As the stop mechanism operates the movement of the locking bolt carrier 175 first to the right, as viewed in Fig. 6, and then to the left, it will raise and lower the rod 204, the rod being moved forwardly by the lever 209 as the projection on the rod passes above the projection on the lever 203 during the upward movement of the rod and actuating the lever 203 during its downward movement, as indicated in Fig. 19, to move the clutch block 197 into engagement with the eccentric 195. To permit the clutch block to move away from the eccentric and thus throw the eccentric out of operation, the rod 204 is moved rearwardly to release the lever 203. This takes place after the eccentric has made a complete revolution. To thus move the lever 209 rearwardly, the lever (see Fig. 23) is provided with gear teeth engaged by teeth on one arm of a lever 211. At its other end the lever 211 is provided with a swinging dog 212 adapted to be engaged by a projection 213 on an arm 214 projecting

from a rock shaft 215 which is rocked forwardly and backwardly during the rotation of the eccentric, the construction being such that during the forward movement of the arm the projection 213 passes the dog 212 without actuating the lever 211, but during the return movement of the arm the engagement of the projection with the dog actuates the lever 211 to return the lever 209 to its original position and thus move the rod 204 out of engagement with the lever 203.

As has been stated, the mechanism actuated by the eccentric 195 includes a rock shaft 215. This rock shaft is below and in vertical alinement with a rock shaft 216 (see Fig. 6), and is connected thereto by a key and slot so that the two shafts turn in unison. At its upper end the shaft 216 is provided with a laterally extending arm 217 (see Figs. 6 and 13) to which is connected the eccentric strap and link 218 of the eccentric 195. From the shaft 216 the welt severing mechanism is actuated and from the shaft 215 the mechanism is actuated through which the jack is depressed and moved outwardly away from the sewing devices and also the mechanism through which a movement is imparted to the pattern cam shaft to complete its rotation so as to cause the jack to be reversely rotated to its initial position. These mechanisms are substantially the same as the corresponding mechanisms of the machine disclosed in Patent No. 1,616,714 except for a provision in the mechanism for depressing the jack and moving it outwardly of means whereby a dwell in the movement of the jack is produced, after it has been depressed, to facilitate the welt severing operation. In the present machine, also, means are provided, actuated from the shaft 215, for moving the jack at the completion of the sewing operation so as to draw welt through the welt guide and thus permit the welt to be severed between the welt guide and the shoe at a sufficient distance from the end of the same to permit the welt to be butted or properly fitted in the subsequent operations which are performed upon the shoe.

For actuating the welt severing mechanism the shaft 216 is provided at its upper end with a laterally extending arm or projection 219 which during its forward movement contacts with an arm 220 and actuates a rock shaft 221 (see Fig. 43) mounted in the frame of the sewing mechanism. This rock shaft forms a portion of the welt severing mechanism which will be herein-after described.

For depressing the jack and moving it outwardly, the rock shaft 215 is provided at its lower end with an arm 222 (see Figs. 6, 21, 40, 41 and 42) carrying bevel gear teeth which mesh with corresponding teeth formed on a segment 223 secured to a short horizontal shaft 224. Upon the shaft 224 a plate-like arm or lever 225 is mounted, the rear side of which during the forward movement of the segment 223 is engaged by a pin 226 projecting from the segment. During a complete rotation of the eccentric 195 the segment 223 is moved forwardly and then rearwardly and during its forward movement the lever 225 is moved from a substantially horizontal position to a vertical position. The lever 225 is retained in its vertical position by the engagement of a spring pressed latch 227 mounted on the lever 225 with a projecting ledge 228 on the machine frame.

The lever 225 depresses the jack and moves it outwardly. At its lower free end the lever is provided with a cross bar 229 which during the forward swinging movement of the lever engages the

80

150

upper surface of a bar 230 (see Figs. 2, 3, 40, 41 and 42) and first depresses the bar and then moves it longitudinally towards the front of the machine. The bar at its forward end is connected by a ball and socket joint to the jack spindle and its rear end is connected by a swivel joint (see Fig. 3) to the lower end of an arm 231 pivotally mounted in a bracket depending from the top plate of the machine base.

10 The welt is severed after the jack has been depressed and before it is moved outwardly, as will be hereinafter described, and in order to cause the jack to dwell in its depressed position during the action of the welt severing mechanism, the 15 teeth on the arm 222 and segment 223 are shaped and arranged to allow a certain amount of lost motion between the arm and segment at about the middle portion of the stroke of the arm.

10 The jack structure is supported so that an upward thrust is normally exerted on the shoe to hold it in contact with the work guiding devices of the sewing mechanism by two cords 500 connected to the horizontal arm 74 of the jack structure and passing over pulleys on the base of the 25 machine and having their opposed ends connected by a spring 600 (see Fig. 9).

After the jack has been moved outwardly away from the sewing devices and while it remains in this position, the completed shoe is removed from 30 the jack and another shoe placed thereon in the same manner as in the machine of Patent No. 1,616,714. As a new shoe is placed on the jack, the jack is pushed downwardly and the downward movement of the bar 230 actuates the latch 35 227 to release the lever 225 and permit it to move rearwardly to its substantially horizontal position. To actuate the latch 227 in this manner, the bar 230 is provided with a projection extending over the cross bar 229 which is movably 40 mounted in the lever 225 and connected by a link with the latch. As the lever 225 swings rearwardly after being released, a spring pressed pin 700 mounted therein actuates the latch 105 to release the lever 104 and leave the controller bar 45 free to be moved (see Figs. 9 and 42).

The final movement of the pattern cam shaft is produced through connections between the pattern cam shaft and the arm 222 at the lower end of the rock shaft 215. These connections 50 consist of a rod 232 (see Figs. 9, 12, 13, 21 and 27), the forward end of which is pivotally connected to the arm 222 and the rear end of which is connected to one arm of a bell crank 233 pivotally mounted on the machine frame, the other arm of 55 which bell crank carries the pivot 191 for the lever 190. As has been described, the lever 190 is actuated by the block 189 on the gear 157 to throw the stop mechanism into operation at the completion of the sewing operation. As the rotation of the pattern cam shaft ceases, the lever 60 190 remains resting upon the block 189 and remains in this position until the eccentric 195 is thrown into operation. During the forward swinging movement of the arm 222 the bell crank 65 233 is rocked in a direction to move the lever 190 bodily so that it drops behind the block 189. As the arm 222 swings back to its original position during the latter part of the rotation of the eccentric 195, the lever 190 acts as a pawl to 70 operate with the block 189 to turn the cam shaft a sufficient distance to complete its revolution. As the cam shaft completes its revolution, the cam levers which engage the cams are permitted to move towards the center of the shaft and thus 75 the jack is reversely rotated and the other parts

of the machine connected to the cam levers are returned to their starting position.

The jack is moved longitudinally at the completion of the sewing operation to draw welt through the welt guide by connections from the bell crank lever 233, which as has just been described, is oscillated by the auxiliary mechanism including the eccentric 195, eccentric link and strap 218, rock shaft 215, arm 222 and rod 232.

These connections include a rod 234 one end of 80 which is connected to one arm of the bell crank 233 and the other end of which has a pin and slot connection with a plate 235 secured to the lower end of a vertical shaft 236 extending axially through a sleeve 237 forming the hub of the rear portion of the jack feeding lever (see Figs. 3, 10, 11 and 13), and provided at its upper end with a cam 238. The feed lever of the present

machine instead of being formed as a rigid frame fast on the sleeve 237 as in the machine of Patent No. 1,616,714, is made in two parts and comprises the arm 89 and a frame 239 secured to the sleeve 237 and having pivoted thereon at its forward end the arm 89. The rear end of the arm 89 is provided with a slot 240 adapted to receive 100

the upper end of the shaft 236 constituting the pivotal axis of the entire feed lever, and the arm is normally held in alinement with the frame 239 so that the entire lever including the arm swings about the axis of the shaft 236 during the sewing 105

operation. The arm 89 is held in alinement with the frame 239 by means of a U shaped spring 241 secured to the upper member of the frame 239 and having one end in engagement with a pin 242

on the frame 239 and the other end engaging a 110 pin 243 projecting downwardly from the arm 89. The longitudinal movement of the jack to draw the welt through the welt guide is produced by a movement of the arm 89 with relation to the

frame 239 from a position in which it is in alinement with the frame to the position indicated in Figs. 10 and 11. This movement of the arm 89 with relation to the frame 239 is produced by the cam 238 which is moved in a counter-clockwise direction by a rocking of the shaft 236 115

during the actuation of the bell crank 233 by the forward swinging movement of the arm 222 (see Figs. 12 and 13). The cam 238 is arranged 120 to engage one end of a short lever 244 (see Fig.

11) pivotally mounted upon the arm 89 and having its other end held in engagement with the pin 243 by a spring 245. The end of the lever 244 in engagement with the cam 238 normally rests in a locking recess 246 and as the cam turns 125

in a counter-clockwise direction the lever 244 which at this time is rigid with the arm 89, is forced to the right as viewed in Fig. 10, and the jack is moved drawing the welt through the welt guide so that the welt may be severed by the

welt severing knives at a substantial distance 130 from the end of the seam. In Fig. 10 the welt severing knives are indicated at 247 and 248 as having just severed the welt and it will be noted from this figure that the welt is severed substantially midway between the welt guide and the

end of the seam. An end of the welt is thus left projecting from the welt guide to start the operation on the next shoe and the length of this end is substantially the same as that left at the completion of the sewing operation. As the welt is 140

severed, the continued movement of the cam 238 in a counter-clockwise direction carries the projection of the cam beyond the lever 244 and permits the lever with the arm 89 to return to their

original positions, thus bringing the parts into 145

150

the position indicated in Fig. 12. At this time, the jack has been moved outwardly away from the sewing devices, as indicated in Fig. 12 so that it can be reversely rotated to its original position 5 when the final movement of rotation is imparted to the pattern cam shaft. The return movement of the bell crank 233 in actuating the pattern cam shaft to cause its rotation acts through the rod 234 to return the cam 238 in a clockwise direction to its original position. During this movement of the cam, the lever 244 yields against the tension of the spring 245 so that no movement of the arm 39 with relation to the frame 239 is produced at this time. A spring 249 connected 10 to the rod 234 tends to hold the rod in its extreme position to the right, as viewed in Figs. 10, 11 and 13.

A feature of the present invention is embodied in means for opening the main driving clutch 20 and thereby stopping the machine and preventing injury to the various parts of the machine or to the shoe in case the stop mechanism fails to operate. In the construction illustrated, this result is secured by the provision of a series of connections which operate to open the main driving clutch in case the lifting of the lever 190 by the block 189 fails to cause an operation of the stop mechanism. These connections include a pivotally mounted lever or frame 250 (see Figs. 2, 14, 25 27, 28 and 29) provided with a roll 251 for engaging the upper surface of the brake member 178 on the sleeve 136. This lever is connected to a vertical actuating rod 252, the lower end of which is provided with a slot arranged to be engaged by a cam projection 253 on a collar 254 loosely mounted upon the hub of the arm 169 secured to the shaft 165 upon which the cam levers, with the exception of the lever 93 which are actuated from the pattern cam shaft, are mounted. The collar 254 is connected by a rod 255 to a frame 256 pivotally mounted on the same pivot shaft with the bell crank lever 233. In the frame 256 a plate 257 is pivotally mounted in position to be engaged by the block 189 on the gear 157 and this plate is provided with an extension 258 overlying the forward end of the lever 190. A spring 259 acts on the rod 255 and through the rod on the frame 256 to hold the right hand end of the frame as viewed in Fig. 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

sion of the sleeve 136 through the rod 252 and lever 250, when the rock shaft 165 is actuated by the arm 167 to withdraw the cam levers from the cams. To cause the collar 254 to be rotated from the shaft 165 it is provided with a shoulder 80 arranged to be engaged by a shoulder on the hub of the arm 169 which is secured to the shaft 165. To permit the collar 254 to be thus actuated without moving the frame 256, the rod 255 is connected to the frame by a pin and slot, as 85 clearly shown in Fig. 27.

In the machine illustrated in the drawings, a series of pattern cams is provided from which a mechanism for slashing the welt during the sewing operation is controlled. These cams are 90 conveniently arranged to alternate on the pattern cam shaft with the cams which are used to actuate the jack feeding lever. One of the jack feeding cams and one of the cams for controlling the welt slashing mechanism are shown in 95 Fig. 31. It will be apparent from this figure that the lever 261 which cooperates with the cam for controlling the operation of the welt slashing mechanism must be moved through a wide arc to clear the other cams on the cam 100 shaft when the shaft is adjusted vertically. A feature of the present invention is embodied in a construction by which the lever 261 can be moved through a wider arc than the other cam levers mounted on the shaft 165, but the same 105 angular movement of the shaft 165 can be utilized to retract all of the levers mounted on this shaft. In the construction illustrated, the lever 261 (see Figs. 27, 31 and 32) is loosely mounted on the shaft 165 and is connected by toggle levers 110 262-263 with a rock shaft 264 mounted in an arm 265 projecting from a hub 266 also mounted on the shaft 165. With this construction, when the toggle levers are in alignment, as illustrated in Fig. 27, the lever 261 is rigidly connected with 115 and in effect forms one part with the arm 265 and hub 266. By turning the rock shaft 264, however, the toggle levers can be moved out of alignment as illustrated in Fig. 31 and the lever 261 swung through a wide arc about the shaft 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

The illustrated machine is provided with mechanism operating, upon the occurrence of a mis-stitch caused by breakage or looseness of the thread, to stop the sewing mechanism and the pattern cam mechanism without throwing the auxiliary mechanism into operation, this stopping 130 mechanism being similar in some respects to that of the machine of Patent No. 1,616,714. The illustrated machine is also provided with mechanism somewhat similar to that of Patent No. 1,616,714 thrown into operation when the sewing mechanism and pattern cam mechanism are stopped on account of the occurrence of a mis-stitch, and acting to turn the pattern cam shaft backwards a predetermined amount. In the construction 135 illustrated (see Fig. 13) this stopping mechanism 140 includes a lever 270 which is actuated upon the occurrence of a mis-stitch to move the lever 188 rearwardly as indicated in Figs. 13 and 22. The connections for so actuating the lever 270 will be 145 hereinafter described. The movement of the lever 150

Another feature of the present invention is 70 embodied in a means for preventing the closing of the main clutch so long as the levers actuated from the pattern cam shaft are in their retracted positions out of engagement with their cams. In the construction illustrated, this result is secured 75 by the rotation of the collar 254 and the depre-

188 to the rear, as indicated in Figs. 13 and 21 withdraws the latch 185 from the rod 182 and sets the stop mechanism into operation in the manner hereinafter described. It will be noted, however, that as the rod 204 rises (see Fig. 18) its lower end will be moved to the right, as viewed in Fig. 18, or to the rear as viewed in Fig. 13 so that upon the downward movement of the rod a shoulder at the lower end of the rod will engage a lever 271 instead of the lever 203. The lever 271 is provided with a set screw 272 (see Figs. 17 and 18) which as the lever 271 is depressed engages the lever 203 back of its pivot and thus depresses the clutch block 197 instead of raising it. The lower end of the clutch block 197 is provided with teeth to engage similar teeth at the upper end of a short vertical shaft 273 so that so long as the block 197 remains depressed, the shaft 273 will be driven from the shaft 198, which as has been hereinbefore stated, is continuously driven from the main driving shaft 137. At its lower end the shaft 273 is provided with a gear 274 meshing with a gear 275 concentric with and secured to the gears 150—151 forming part of the gear train through which the pattern cam shaft is driven. The construction is such that the rotation of the shaft 273 in the manner described, imparts a reverse rotation to the pattern cam shaft. To prevent a reverse rotation of the cam shaft of the sewing mechanism the pattern cam shaft is thus driven backwardly, a lever 276 is provided (see Figs. 13 and 17 to 20 inclusive) which lever is pivotally mounted on the pivot stud of the lever 271 and engages at its forked rear end with a groove in the clutch block 145 at the lower end of the shaft 144. The lever 276 is provided with a projection 277 arranged to be engaged by a projection 278 on the lever 271 so that the lever 276 is actuated when the lever 271 is depressed and raises the clutch block 145 out of engagement with the clutch 146 against the tension of the springs 279. A spring plunger 280 mounted in the lever 276 and bearing against a portion of the lever 271 normally maintains the projections 277 and 278 in contact, but permits an upward independent movement of the lever 271 when the lever 203 is depressed as has been hereinbefore described, to raise the clutch block 197.

After the cam shaft has been driven backwardly, the desired distance, the lever 271 is released and the clutch block 197 is raised to disconnect the pattern cam shaft from the reverse driving mechanism. The release of the lever 271 is effected by moving the lower end of the rod 204 out of engagement with the lever. The rod is moved by the levers 209 and 211 hereinbefore described, the lever 211 being provided with a series of gear teeth 281 meshing with a corresponding series on a disk 282 which after a partial rotation of the shaft 198 is rotated by the shaft to actuate the levers 211 and 209 (see Fig. 21). The disk 282 is actuated from the shaft 273 through a ring 283 surrounding the shaft and adapted to be driven therefrom in one direction by a ball clutch, but permitting an independent rotation of the shaft in the opposite direction. The shaft 273 is geared to the pattern cam shaft as has been described and during the normal operation of the machine the shaft 273 rotates in a clockwise direction. Its rotation in this direction moves the ring 283 frictionally until its movement is stopped by the engagement of a radial projection 284 with a projection 285 on the flange of a sleeve 286 surrounding the shaft 273. The sleeve 286 is connected by a rod 287 to the arm 102 of

the speed changing mechanism hereinbefore described so that the position of the projection 285 and consequently the initial angular position of the ring 283 is varied with the size of the shoe being operated upon. The normal position of the ring 283 is indicated in Fig. 21. When the reverse driving mechanism is thrown into operation the ring is driven by the shaft 273 which is rotating in a counter-clockwise direction until the radial lug 284 engages an upwardly extending cam projection 288 on the disk 282. Continued rotation of the ring actuates the disk 282 to move the levers 211—209 as has hereinbefore been described, and at the same time the cam projection 288 engages a projection on the lever 203 (see Fig. 18) and positively disengages the clutch block 197 from the shaft 273.

A mis-stitch may occur near the end of the seam and after the block 189 of the stopping mechanism has moved beneath the lever 190. The provision of the dog 194 hereinbefore described, however, between the lever 188 and the rod 192 permits the mis-stitch stop mechanism to operate at this time, the dog being arranged so that during the movement of the lever 270 the dog is first swung out of engagement with the rod 192 and then forms a rigid connection between the lever 188 and the lever 270.

A mis-stitch also sometimes occurs at the beginning of a seam and in order to avoid injury to the machine by a reverse rotation of the pattern cam shaft beyond its initial starting position, a feature of the present invention is embodied in devices for throwing out the reverse driving mechanism when the pattern cam shaft is returned to starting position. In the construction illustrated (see Figs. 21, 22 and 23) the lever 211 is provided with a projection 289 which when the reverse driving mechanism is thrown into operation extends over the projection 213 on the arm 214 of the shaft 215. When the pattern cam shaft is in its initial position, the relative positions of the block 189 and lever 190 are as indicated in Fig. 13 in which figure it will be seen that the forward end of the lever 190 rests behind the block. In case of a mis-stitch at the beginning of the seam, a backward rotation of the pattern cam shaft will bring the block 189 into contact with the lever 190 and force it backwardly, thereby rocking the bell crank 233 and 125 through the rod 232 and arm 222 rocking the shaft 215 and moving the arm 214 in a direction to cause the projection 213 on the arm to actuate the lever 211 to the same extent that it would be actuated by the disk 282 if a mis-stitch occurred elsewhere in the seam.

On account of the number of gears in the trains through which the pattern cam shaft is driven both forwardly and backwardly considerable strain is brought upon the auxiliary mechanism in completing the rotation of the pattern cam shaft. A feature of the present invention is embodied in a construction for lessening this strain, means being provided in the illustrated machine for moving the shaft 153 axially (see Figs. 24, 25 and 26) to throw the gears 151 and 152 out of mesh prior to the final actuating of the pattern cam shaft to thereby disconnect from the pattern cam shaft a number of the gears composing the direct and reverse drives. For axially moving the shaft 153, a bell crank lever 290 is provided, the horizontal arm of which has a gear tooth and rack engagement with a sleeve 291 on the shaft and the vertical arm of which engages an inclined slot 292 in a slide 293. A

cam 294 on the hub of the arm 222 at the lower end of the shaft 215 is arranged to move the slide 293 in a direction to cause the shaft 153 to be depressed so as to move the gear 152 out of mesh with the gear 151. The shaft 153 is raised to return the gear 152 into mesh with the gear 151 by a lever 295, one end of which engages a roll 296 on the slide 293 and the other end of which engages a shoulder on the treadle actuated rod 107.

The sewing mechanism of the illustrated machine has the same general mode of operation in handling the thread and in feeding the work as the sewing mechanism disclosed in Patent No. 1,616,714, or in applicant's prior patent, No. 1,397,013 dated November 15, 1921. The work engaging parts of the sewing mechanism are adapted to feed the shoe continuously through the machine and the thread handling devices operate to form a chain stitch, the chain of which is laid upon the welt. In the formation of each stitch, a stitch setting strain is exerted upon the thread while the needle is in the work and at the conclusion of the sewing as the machine is stopped the needle is brought to rest in retracted position with its hook free of the thread, as is the common practice in this class of machines. The parts of the sewing mechanism illustrated include a curved hook needle 297, a needle guide 298, a looper 299, a thread finger 300, a channel guide roll 301, a welt guide 302, a take-up 303, an auxiliary take-up 304 and a tension wheel 305.

The needle is clamped to a needle carrier 306 formed with laterally extending bearing studs 35 journaled in forwardly projecting portions of the sewing machine frame as best shown in Fig. 52. To oscillate the needle, a bell crank lever 307 (see Fig. 45) is loosely mounted upon a shaft 308, the lower arm of which bell crank lever is connected to the needle segment by a link 309 while the upper arm of the bell crank lever is connected to an actuating crank 310 on the actuating cam shaft 311 of the sewing mechanism by means of a pitman 312. The needle carrier 40 also has a lateral movement to impart work feeding and return movements to the needle and accordingly a universal joint is provided at each end of the connecting link 309. These lateral movements are imparted to the needle carrier by 45 two levers 313 and 314 mounted respectively on the pivot shafts 315 and 316 (see Fig. 52) and engaging at their forward ends the ends of the bearing studs of the needle carrier. The levers 313 and 314 are connected by a link 317 and the lever 314 is provided with a rearward extension carrying a roll engaging a cam on the cam shaft 311.

The needle guide 298 (see Figs. 48, 49, 51, and 52) is formed integrally with a sleeve mounted on 60 one of the bearing studs of the needle carrier and is provided with segmental gear teeth 318 which are engaged by rack teeth on a slide 319. This slide is actuated from the cam shaft 311 through yielding connections whereby the needle guide is 65 pressed yieldingly against the work during the passage of the needle therethrough and a locking device for the slide is provided whereby the needle guide may be locked rigidly in position against the work regardless of its thickness during the re- 70 tracting stroke of the needle. The general operation of this actuating and locking mechanism is the same as the mechanism disclosed in applicant's prior application, Serial No. 260,419, filed October 31, 1918, on which Patent No. 1,739,534 75 issued on January 20, 1931, but in the illustrated

machine these results are secured in a simplified and improved manner. The device for locking the slide 319 to hold the needle guide in contact with the work during the retracting stroke of the needle comprises a roll 320 resting on an inclined surface formed on the slide and supported by a spring pressed plunger 321, the arrangement being such that with the parts in the position illustrated in Fig. 49 the slide 319 is locked against forward movement by the wedging of the roll 320 between the slide and the upper surface of its guideway in the machine frame. The slide 319 is actuated from the cam shaft 311 through a cam actuated lever 322, a connecting link 323, a block 324 through which a rearward extension of the slide 319 passes and a spring 325 surrounding the extension of the slide 319 and interposed between the block 324 and a pin 326 at the rear end of the extension. With this construction, a yielding rearward movement is imparted to the slide 319 to press the needle guide yieldingly against the work. To release the locking roll 320 and permit the slide 319 to be moved forwardly by the forward reciprocation of the block 324, a rod 327 is mounted in the slide 319 with its forward end in engagement with the roll and with its rear end in position to be engaged by the block 324 during its forward movement.

The looper mechanism of the illustrated machine is similar to the looper mechanism disclosed in applicant's prior Patent No. 1,543,265, dated June 23, 1925. An improved construction is, however, provided in the illustrated machine for preventing the looping of the needle during the last cycle of operations of the sewing mechanism so that the needle may be stopped in retracted position free of the thread. In the illustrated construction, the looper 299 (see Fig. 46) consists of a tubular lever projecting downwardly from a support 328 and mounted therein by means of a universal joint consisting of a ball formed at the upper end of the looper lever and a correspondingly shaped socket formed in the support. The looper is actuated to carry its lower end around the needle so as to thread the hook of the needle by means of two cam actuated bell crank levers 329 and a triangularly shaped lever or link 330 connected to the bell crank levers and to the looper lever by universal joints, as in the construction disclosed in Patent No. 1,543,265. To prevent the needle from being threaded during the last cycle of operations of the sewing mechanism, the illustrated machine is provided with means for moving the support 328 so as to raise the looper in a direction substantially lengthwise of the needle. In the construction illustrated, the support 328 is pivotally mounted on the frame of the machine and is normally held by a spring 331 in a position in which the thread will be laid by the looper in the hook of the needle. A rod 332 mounted for convenience in the pivot stud 333 of the welt guide actuating lever hereinafter described is arranged with its forward end adapted to contact with a downward projection from the support 328 and with its rear end in the path of movement of a projection 334 on a collar 335 fast on the pivot shaft 308. This shaft is rocked in a clockwise direction, as viewed in Fig. 46, during the operation of the stop mechanism in throwing out the driving mechanism of the sewing cam shaft and the pattern cam shaft hereinbefore described. The mechanism for rocking the shaft 308 is illustrated in Figs. 6, 7 and 43 and comprises a forward extension of the arm 206, a gear seg- 150

ment 337 at the forward end of the arm and a segmental gear 338 secured to the shaft 308.

The thread finger 300 of the illustrated machine is formed on the forward end of a slide 5 mounted to reciprocate in a guideway in the frame of the machine. This thread finger cooperates with the looper in supplying thread to the needle during each stitch forming cycle and like the thread finger of the machine disclosed in 10 Patent No. 1,616,714 is also utilized at the conclusion of the sewing operation as a part of a mechanism for severing and holding the thread between the looper and the work. The illustrated machine is, however, provided with a simplified and improved means for actuating the thread finger. In the construction illustrated (see Figs. 47, 48, 49, 51, 59, 60 and 61) the rear end of the thread finger slide is provided with rack teeth which are engaged by a gear segment 339 pivotally 15 mounted upon the pivot shaft 315. The hub of this segment is provided with spiral gear teeth meshing with corresponding gear teeth on the hub of a cam actuated lever 340 pivotally mounted upon the rock shaft 308. The lever 340 is provided with a cam roll 341 which during 20 the normal sewing operation of the machine is in engagement with a cam groove 342 formed in a cam disk 343 secured to the cam shaft 311, as indicated in Fig. 47. The movements imparted to the thread finger by the cam groove 342 are merely sufficient to measure off the thread between the needle and the looper during each 25 cycle of operations of the sewing devices. To cause the thread finger to cooperate with the other devices of the mechanism for cutting and holding the thread at the conclusion of the sewing operation, the cam roll 341 is switched into an auxiliary cam groove 344 in the cam disk 343 as will be described. The position of the 30 thread finger is thus changed and during the actuation of the lever 340 by the groove 344, the thread is cut and held. The devices cooperating with the thread finger in cutting and holding the thread comprise a spring pressed slide 345 the forward end of which is arranged to 35 cooperate with the thread finger in gripping and holding the thread and a fixed cutting blade 346 across which the thread is carried by the thread finger after it has been gripped between the finger and the slide 345.

For switching the cam roll 341 from the groove 342 to the groove 344, a switch cam disk 347 is provided which is mounted in a cylindrical recess in the cam disk 343, as illustrated in Figs. 59, 60 and 61. The disk 347 is held in the recess 40 in the cam disk 343 by a screw 348, the head of which extends over a flange on the switch cam disk, and by a key 349 engaging a slot in the edge of the switch cam disk and removably secured to the cam disk 343 by the screws 350. The switch cam disk is provided with two grooves 351 and 352 extending across the face of the disk and with a rib 353 separating the grooves and projecting at each end beyond the periphery of 45 the disk, the rib extending substantially diametrically across the face of the disk. It will be apparent from an inspection of Figs. 48, 49 and 59 that the switch cam disk is movable from the position indicated in Fig. 59 to that indicated in Figs. 48 and 49, and that the movement 50 of the disk to the position indicated in Figs. 48 and 49 back to the position indicated in Fig. 59 is limited by the engagement of the projecting ends of the rib 353 with the walls of the cam 55 grooves in the cam disk 343. Also, it will be seen

that with the switch cam disk in the position indicated in Fig. 59, the cam roll 341 can remain in the groove 342 during the continued rotation of the cam disk 343, and that while the roll 341 is passing through the groove 351 in the switch cam the lever 340 can be moved to rotate the switch cam and transfer the roll to the groove 344 as indicated in Fig. 49. The cam lever 340 is moved to transfer the cam roll 341 from one groove to the other from the rock shaft 308 which as has hereinbefore been described is rocked in a clockwise direction during the operation of the stop mechanism at the conclusion of the sewing operation at a predetermined point in the cycle of operations. The lever 340 is provided with a rearward projection 354 to which is attached a spring 355 tending to swing the lever about the shaft 308 in a clockwise direction. The shaft 308 is provided with a pin 356 which projects radially through a circumferential slot in the hub of the lever 340, the slot being of sufficient length to allow for the oscillation of the lever 340 during the normal operation of the sewing mechanism without moving the shaft 308. When, however, the shaft 308 is rocked at the 100 conclusion of the sewing operation, the pin 356 engages the right hand end of the slot in the hub of the lever 340 and swings the lever in a counter-clockwise direction, this action taking place at the time in the cycle of operations of the sewing mechanism when the roll 341 of the lever 340 is slightly below the center of the switch cam 105 347. As the upper end of the lever 340 swings outwardly, the parts assume the position indicated in Fig. 49, and during the continued 110 rotation of the shaft 311, the roll 341 travels along the cam groove 344 until the cam shaft is stopped in the position indicated in Fig. 48. The outward movement of the upper end of the lever 340 produces a sufficient movement of the thread 115 finger to cause the thread to be cut and held. When the sewing mechanism is again thrown into operation, the cam roll 341 of the lever 340 travels along the cam groove 344 and through the groove 352 of the switch cam lever, thereby 120 moving the switch cam back to the normal position, indicated in Fig. 59. The roll 341, however, continues on in the groove 344 for a complete revolution of the cam shaft 311 and then passes along the groove 351 of the switch cam into the 125 cam groove 342. A detent in the form of a spring pressed ball 357 mounted in the cam disk 343 is arranged to engage one of two recesses 358 formed in the switch cam disk and tends to retain the switch cam disk in each of its positions. 130

The channel guide roll 301 is arranged and actuated as in the machine of Patent No. 1,616,714 being mounted upon the lower end of an obliquely arranged shaft, and being driven continuously through spiral gears from the cam shaft 311. 135

The welt guide 302 is carried upon the lower end of a welt guide carrier 359 mounted to move towards and from the shoe in an arcuate guideway having a curvature substantially concentric with the axis about which the needle oscillates. 140 This arcuate guideway is formed in a slide 360 (see Figs. 53, 54 and 55) which during the sewing operation is reciprocated back and forth in the line of feed. The slide 360 is mounted upon a guide rod 361 and is also guided by a rod 362 145 which is engaged by a rearward extension of the slide. For reciprocating the slide 360 a cam actuated lever 363 is provided pivoted upon the stud 333 hereinbefore referred to and having its lower end pivotally connected to the slide while 150

its upper end is provided with a roll engaging a groove in one of the cam disks on the cam shaft 311. The welt guide is yieldingly pressed towards the work by a spring 364 (see Figs. 44, 45 and 47) through connections which include a lever 365 pivotally mounted upon the rod 362 and having at its forward end a gear segment engaging a corresponding gear segment on the welt guide carrier 359. Upon the rear end of the lever 10 365 a bell crank lever is mounted, the horizontal arm of which is connected to the spring 364 and the vertical arm of which is pivotally connected to a link 366 forming a part of the welt slashing mechanism hereinafter described. The link 366 15 at its forward end is pivotally connected to the upper end of a lever 367 mounted on the lever 365 and also forming a part of the welt slashing mechanism. Intermediate its ends the link 366 is provided with a pin 368 which projects laterally 20 on each side of the link and is arranged to engage a shoulder on the lever 365. The spring 364, therefore, tends to force the link 366 forwardly and while the pin 368 is in engagement with the lever 365, to raise the rear end of the lever and 25 thus force the welt guide towards the work. To lock the welt guide against backward movement during the retracting stroke of the needle, the rear end of the link 366 is provided with a series of teeth arranged to be engaged by corresponding 30 teeth on a cam actuated locking lever 369. While the needle is in the work, the lever 369 is actuated to unlock the welt guide and permit the guide to be back-fed while the work continues to be fed forward by the needle.

35 The take-up 303 (see Figs. 7, 43 and 44) comprises a roll mounted upon a stud 370, the ends of which are mounted to reciprocate in substantially horizontal slots formed in upwardly extending plates 371 of the machine frame and connected to the forward ends of the sides of a U shaped link 372, the rear end of which is pivotally connected to a cam actuated lever 373.

The auxiliary take-up 304 comprises a roll over which the thread passes on its way from the 40 take-up to the looper mounted in the upper end of a spring pressed arm 374 (see Figs. 43, 48 and 49). Except for the construction herein-after described which adapts it for cooperation with the mis-stitch stop mechanism this auxiliary take-up is of usual construction.

The tension wheel 305 is of usual and well-known construction, as is also the wax pot indicated at 375.

The welt slashing devices of the illustrated 45 machine comprise a welt slashing knife 376 (see particularly Figs. 56, 57 and 58) projecting from a slide 377 mounted to reciprocate transversely of the welt in a guideway formed in the welt guide. While the welt slashing mechanism is 50 inactive, the welt slashing knife is held out of engagement with the welt by means of a spring 378 acting upon a pin 379 projecting from a lug at the rear end of the slide 377 into a recess in the welt guide. When the welt slashing mechanism is active, the welt slashing knife is actuated during each stitch forming cycle by a rearward movement of the link 366 hereinbefore referred to and an oscillation of the lever 367, the lower end of which is arranged to contact with the rear 55 end of the slide 377. For actuating the link 366 and lever 367 a projection 380 is provided at the lower end of the lever 307 forming a part of the needle actuating mechanism which is arranged to move the link rearwardly each time the needle 60 approaches its forward limit so long as the welt

slashing mechanism is active. The rear end of the link 366 is provided with a roll 381 which so long as the welt slashing mechanism remains inactive is not engaged by the projection 380. To render the welt slashing mechanism active, a dog 80 382 is interposed between the roll 381 and the projection 380 so that the movement of the projection 380 is transmitted to the roll and the link 366 is moved rearwardly. To permit the link 366 to move forwardly and the welt slashing 85 knife to be retracted during the retracting stroke of the needle, the dog 382 is pivotally mounted at 383 and is held yieldingly in position by a spring 384. To relieve the pressure of the welt guide on the work during the action of the welt slashing knife and also to relieve the pressure of the welt guide on the work during the back feed of the welt guide, a cam surface is formed on the lower end of the lever 307 which is arranged to engage the roll 381 and force the roll and consequently the rear end of the link 366 and of the lever 365 downwardly. As has been stated, the operation of the welt slashing mechanism is controlled from cams on the pattern cam shaft, the cams being so shaped that 90 the welt slashing mechanism is thrown into and out of operation at the desired times during the sewing of the inseam. In the construction illustrated, the connections actuated by the lever 261 which cooperates with the cam on the pattern 100 cam shaft for controlling the operation of the welt slashing mechanism (see Figs. 6, 10 and 31) comprise a link 386 connecting an arm on the hub 266 of the lever 261 with an arm projecting from a vertical rock shaft 387 another arm of 105 which is connected by a link 388 to the vertical arm of a bell crank lever 389. The horizontal arm of the lever 389 is connected by a rod 390 to a lever 391 upon the forward end of which the dog 382 is mounted.

110 The devices of the illustrated machine for severing the welt in the manner hereinbefore described comprise the welt cutting blades 247 and 248 of which the blade 247 is arranged to pass over the welt and has a movement transversely 115 of the welt only, and of which the blade 248 passes below the welt or between the welt and the shoe and has a movement both transversely of the welt and towards and from the blade 247. In the construction illustrated (see Figs. 44, 47 120 and 62 to 65 inclusive) the cutter blade 247 is formed at the forward end of a tubular slide 392 mounted to reciprocate in the frame of the machine, its forward movement being limited by a screw 393 projecting from the machine frame 125 into a slot 394 in the slide. The cutter blade 248 is supported on the blade 247 and slide 392 by screws 395 and 396 of which the screw 395 passes through a curved slot 397 in the blade 248 and screws into the blade 247 and of which the screw 130 396 has a bearing in the blade 248 and passes through a longitudinal slot 398 in the slide 392, and screws into the forward end of a connecting rod 399. A coil spring 400 is interposed between the forward end of the connecting rod 399 and a 135 pin 401 extending transversely across the forward end of the tubular slide 392. With this construction, a forward movement of the connecting rod 399 causes both cutter blades to be carried forward until the rear end of the slot 140 394 strikes the screw 393. In this position of the parts the cutter blade 247 extends over the welt and is at the limit of its outward movement. Continued movement of the connecting rod 399 145 compresses the spring 400 and moves the blade 150

248 outwardly and upwardly with relation to the blade 247, thus severing the welt and bringing the parts into the position indicated in Fig. 63. Backward movement of the rod 399 returns the 5 parts to the position indicated in Figs. 62 and 64. The rod 399 is connected at its rear end to an arm 402 extending downwardly from the rock shaft 221 which is actuated in the manner hereinbefore described by the auxiliary mechanism 10 which depresses the jack after the completion of the sewing operation.

The mis-stitch stop mechanism of the illustrated machine is controlled by the auxiliary take-up, the improved mechanism embodying this 15 feature of the present invention being illustrated in detail in Figs. 66, 67 and 68. Referring to these figures, 403 indicates a slide which is reciprocated during each stitch forming cycle of the machine by means of a cam actuated lever 20 404, the rear end of which engages a cam on the cam shaft 311 of the sewing mechanism and the front end of which is connected by a link 405 to the horizontal arm of a bell crank 406, the vertical arm of which is pivotally connected to 25 the rear end of the slide 403. The bell crank 406 is pivotally mounted upon a three armed support 407, the downwardly extending arm of which is pivotally mounted on a projection from the machine frame, the upwardly extending arm 30 of which is adapted to engage a stop projection 408 on the machine frame and the horizontally extending arm of which engages the upper end of a thrust rod 409. The lower end of the thrust rod 409 rests upon the horizontal arm of a bell 35 crank 410, the vertical arm of which engages the lever 270 of the mechanism for throwing the stop mechanism into operation hereinbefore described. The arm 374 of the auxiliary take-up is provided 40 with an abutting surface 411, which as the auxiliary take-up rises and falls during the formation 45 of each stitch on account of the varying tension on the thread is moved into and out of the path of movement of the slide 403. The movements of the slide 403 are timed with relation to the 50 stitch forming cycle so that the forward movement of the slide takes place while a sufficient tension is exerted on the thread to raise the auxiliary take-up into a position in which the surface 411 is out of the path of movement of the 55 slide. In case of a mis-stitch due to breaking of the thread or for other cause, the tension on the thread will be relieved and when the slide 403 makes its forward movement it will engage the surface 411 on the arm of the auxiliary take-up. This will stop the movement of the slide and continued downward movement of the forward 60 end of the cam lever 404 will rock the three arm support 407 about its pivotal connection with the frame of the machine and through the rod 409 and bell crank 410 throw the mis-stitch stop mechanism into operation in the manner hereinbefore described.

To prevent the mis-stitch stop mechanism from being thrown into operation during the first 65 cycle of operations of the stitch forming mechanism in case the machine is started while the thread is slack or while the end of the thread is held by the operator instead of by the thread holder, the illustrated machine is provided with 70 means which acts during the first stitch forming cycle to hold the auxiliary take-up in its raised position. In the illustrated construction, this means comprises a rod 412 (see Figs. 47 to 50 inclusive), the forward end of which is arranged 75 to engage an arm 413 secured to the pivot stud

of the arm 374 of the auxiliary take-up and the rear end of which is arranged to engage the cam lever 340 which actuates the thread arm. As has been described, the roll 341 of the lever 340 is in the outer cam groove 344 when the sewing mechanism stops and remains in this groove during the first cycle of operations of the stitch forming devices in sewing the next shoe. While the roll 341 remains in the groove 344, the lever 340 is in a position in which the rod 412 holds the auxiliary take-up raised so that the mis-stitch stop mechanism can not be thrown into operation. A spring 414 surrounding the rod 412 acts on a collar 415 secured to the rod to hold the rod normally in a position in which the auxiliary 80 take-up is free to move.

It will be noted that the thread arm during the last cycle of operations of the stitch forming devices moves to the rear a considerable distance from its normal position and consequently draws 85 out more thread than is supplied by the other stitch forming devices to the arm. To provide the requisite amount of thread for the thread arm during its abnormal movement at the conclusion of the stitch forming operation, a pull-off 90 is provided in the illustrated machine arranged to engage the thread between the tension wheel and the work, which pull-off is thrown into operation from the stop mechanism to pull off a supply of thread for the thread arm to operate 95 upon. This pull-off is indicated at 416 (see Figs. 3, 43 and 44) and comprises a pin mounted at the upper end of a lever 417. The other arm of this lever is connected by a link 418 to an arm 419 secured to the shaft 308 which shaft is actuated 100 from the stop motion at the conclusion of the 105 sewing operation, as has hereinbefore been described.

Certain features of the machine herein disclosed form the subject-matter of divisional applications as follows: Serial No. 358,342 filed April 26, 1929, Shoe machine, on which Patent No. 1,834,471 issued on December 1, 1931; Serial No. 566,475 filed October 2, 1931, Sewing machine, on which Patent No. 1,907,434 issued May 120 9, 1933; and Serial No. 693,285 filed October 12, 1933, Stopping mechanisms for sewing machines.

The nature and scope of the present invention having been indicated and an embodiment of the several features of the invention having been specifically described, what is claimed is:

1. A machine for attaching a welt to a shoe bottom having, in combination, welt attaching means, a welt guide, means for relatively moving the shoe and welt guide after the completion of 130 the welt attaching operation to draw welt through the welt guide, and means for severing the welt between the shoe and welt guide.

2. A machine for sewing inseams of welted shoes having, in combination, stitch forming devices, and means acting automatically at the end of the sewing operation to sever the welt at a distance from the end of the seam greater than a stitch length.

3. A machine for attaching a welt to a shoe 140 bottom having, in combination, welt attaching means, a welt guide, means for moving the shoe after the completion of the welt attaching operation to draw welt through the welt guide, and means for severing the welt between the shoe 145 and welt guide.

4. A machine for attaching a welt to a shoe bottom having, in combination, welt attaching means, a welt guide, a shoe supporting jack, means for moving the jack in the direction of 150

- feed after the completion of the welt attaching operation to draw welt through the welt guide, and means for severing the welt between the shoe and guide.
5. A machine for attaching a welt to a shoe bottom having, in combination, welt attaching means, a welt guide, means for moving the shoe out of operating position after the completion of the welt attaching operation, and means for thereafter severing the welt between the shoe and guide.
6. A machine for attaching a welt to a shoe bottom having, in combination, welt attaching means, a welt guide, a shoe supporting jack movable to transfer the point of operation about the shoe, means for depressing the jack after the completion of the welt attaching operation, and means for severing the welt between the shoe and guide while the jack is depressed.
20. A machine for attaching a welt to a shoe bottom having, in combination, welt attaching means, a welt guide, a shoe supporting jack, means for moving the jack in the direction of feed after the completion of the welt attaching operation to draw welt through the welt guide, means for severing the welt between the shoe and guide, means for moving the jack in the opposite direction, and means for turning the jack to its initial position.
30. A machine for attaching a welt to a shoe bottom having, in combination, welt attaching means, a welt guide, a shoe supporting jack movable to transfer the point of operation about the shoe, means for depressing the jack after the completion of the welt attaching operation, means for moving the jack in the direction of feed after the completion of the welt attaching operation to draw welt through the welt guide, and means for severing the welt between the shoe and guide.
40. A machine for attaching a welt to a shoe bottom having, in combination, welt attaching means, a welt guide, a shoe supporting jack, means for imparting to the jack a movement in the direction of feed and an equal return movement after the completion of the operation on the shoe, and means for severing the welt between the guide and shoe while the jack is at the limit of its movement in the direction of feed.
50. A machine for attaching a welt to a shoe bottom having, in combination, welt attaching means, a welt guide, a welt slashing knife mounted on the welt guide, means for moving the welt guide back and forth in the line of feed, and means for actuating the knife to slash the welt.
55. A machine for attaching a welt to a shoe bottom having, in combination, welt attaching means, a welt slashing knife, means for actuating the knife to slash the welt, and means for moving the knife in the direction of feed with the welt while engaged with the welt.
60. A machine for attaching a welt to a shoe bottom having, in combination, welt attaching means, a welt guide, a welt slashing knife mounted in the welt guide, and means for retracting the welt guide and simultaneously actuating the slashing knife to slash the welt.
65. A machine for attaching a welt to a shoe bottom having, in combination, welt attaching means, a welt guide, a welt slashing knife mounted in the welt guide, mechanism for intermittently retracting the welt guide, and means for causing said mechanism to actuate the welt slashing knife to slash the welt.
70. A machine for attaching a welt to a shoe bottom having, in combination, welt attaching means, a welt guide, a welt slashing knife mounted in the welt guide, mechanism actuated by the cam shaft for changing the relative positions of the jack and welt attaching means during the welt attaching operation, and mechanism controlled from the cam shaft for actuating the knife to slash the welt.
75. A machine for sewing inseams of welted shoes having, in combination, stitch forming devices including a curved hooked needle entering from the welt side of the work, a slide mounted to reciprocate in the direction of feed, and a welt guide mounted in an arcuate guideway having the needle axis as its center of curvature.
15. A machine for sewing inseams of welted shoes having, in combination, stitch forming devices, a welt guide, a welt guide carrier mounted to move toward and from the shoe, an actuating lever engaging the carrier, a spring for moving the welt guide towards the shoe, and a cam for actuating the lever to move the welt guide away from the shoe.
16. A machine for sewing inseams of welted shoes having, in combination, stitch forming devices, a welt guide, a welt guide carrier mounted to move toward and from the shoe, an actuating lever intergeared with the welt guide carrier, and means for oscillating the lever to move the welt guide carrier toward and from the shoe.
17. A machine for sewing inseams of welted shoes having, in combination, stitch forming devices including a curved hooked needle entering from the welt side of the work, a slide mounted to reciprocate in the direction of feed and provided with an arcuate guideway, a welt guide, a welt guide carrier mounted in said guideway to move toward and from the shoe, an actuating lever intergeared with the welt guide carrier, and means for oscillating the lever to move the welt guide carrier toward and from the shoe.
18. A machine for sewing inseams of welted shoes having, in combination, stitch forming devices, a welt guide, a welt guide carrier mounted to move toward and from the shoe, an actuating lever engaging the carrier, a spring for moving the welt guide towards the shoe, a cam for actuating the lever to move the welt guide away from the shoe, and means for locking the welt guide against movement away from the shoe.
19. A sewing machine having, in combination, stitch forming devices including a thread finger, a cam follower and suitable connections for actuating the thread finger, a cam provided with two cam paths to engage the follower, a switch to direct the follower from one path to the other, means operating on stopping the machine to render the switch operative, and means cooperating with the thread finger after the switch has operated on the cam follower to sever and hold the thread.
20. A machine for operating on shoes having, in combination, devices for operating on a shoe, actuating mechanism therefor including a cam follower and suitable connections, a cam provided with two cam paths to engage the follower, a switch, and means operating on stopping the machine to render the switch operative to direct the follower from one cam path into the other.
21. A machine for operating on shoes having, in combination, devices for operating on a shoe, actuating mechanism therefor including a cam follower and suitable connections, a cam provided with a main cam path and an auxiliary cam path to engage the follower, a switch, means operating on stopping the machine to render the switch operative to direct the follower from the main cam path into the auxiliary cam path, and means whereby the follower shifts the switch during the first revolution of the cam on starting the machine to direct the follower from the auxiliary

cam path into the main cam path during the second revolution of the cam.	point, and mechanism operable after the completion of stitching for causing the advance of the work and welt before severing, to carry the stitched part of the work and welt beyond the cutting point, and for causing the actuation of the cutter.	80
22. A machine for operating on shoes having, in combination, devices for operating on a shoe, actuating mechanism therefor including a cam follower and suitable connections, a cam provided with two cam paths to engage the follower and with a movable switch portion, and means operating on stopping the machine to move the switch portion to direct the cam follower from one cam path into the other.	24. In a welt sewing machine, a shaft, a needle operated from the shaft, a welt guide adjacent the stitching position delivering the welt to the work, and means constituting a part of the machine and adapted to be operated after the completion of a seam for bringing about a substantial advance of the work and the pulling of welt through the guide before severing.	85
23. In a welt sewing machine, a reciprocating needle, a welt guide adjacent the stitching point delivering the welt to the work, a cutter fitted to 15 cut the welt substantially beyond the stitching	ALFRED R. MORRILL.	90
